CLAIM

The ornamental design for a dispenser, as shown and described.

DESCRIPTION

FIG. 1 is an orthographic view of a dispenser embodying our new design;

FIG. 2 is a front view of the dispenser shown in FIG. 1;
FIG. 3 is a rear view of the dispenser shown in FIG. 1;
FIG. 4 is a right-side view of the dispenser shown in FIG. 1;
FIG. 5 is a left-side view of the dispenser shown in FIG. 1;
FIG. 6 is a top view of the dispenser shown in FIG. 1;
FIG. 7 is a bottom view of the dispenser shown in FIG. 1;
and,

FIG. 8 is an orthographic, environmental view of the dispenser shown in FIG. 1 installed within a wall.

The broken lines in the drawings show unclaimed subject matter only and form no part of the claimed design.

1 Claim, 8 Drawing Sheets
